Primary Examiner — Sanjeev Paul(57) **CLAIM**

The ornamental design for a holder for microscope slides, as shown and described.

DESCRIPTION

1. Holder for microscope slides

1.1 : Front

1.2 : Back

1.3 : Left

1.4 : Right

1.5 : Top

1.6 : Bottom

1.7 : Cross sectional

1.8 : Enlarged

1.9 : Perspective

1.10 : Perspective

1.11 : Enlarged

1.12 : Enlarged

This article is a holder for microscope slides that holds a plurality of microscope slides, each of which is a rectangular glass plate to be observed with a microscope, the rectangular glass plate being arranged side by side; the indicator line in FIG. 1.1 indicates the cross-sectional position; the indicator lines in FIGS. 1.7, 1.9 and 1.10 represent the expansion range.
